UNITED STATES PATENT OFFICE.

WILLIAM J. HUTCHINS, OF JOLIET, ILLINOIS.

WIRE-NAIL MACHINE.

SPECIFICATION forming part of Letters Patent No. 365,687, dated June 28, 1887.

Application filed December 29, 1886. Serial No. 222,939. (No model.)

To all whom it may concern:

Be it known that I, WILLIAM J. HUTCHINS, a citizen of the United States of America, residing at Joliet, in the county of Will and State of Illinois, have invented certain new and useful Improvements in Wire-Nail Machines, of which the following is a specification, reference being had therein to the accompanying drawings.

10 This invention relates to certain improvements in wire nail machines, the construction and operation of which are fully set forth and explained in the following specification and claims, reference being had to the accompanying drawings, and the letters of reference marked thereon, which form a part of this specification, in which—

Figure 1 is a top plan view of the machine. Fig. 2 is a detail plan view of that portion of the gripping - dies, heading - tool, and wire-guide which serves to grip, head, and, in conjunction with one of the point-cutters, cut the nail loose from the wire, and also a top plan view of the lower point-cutter. Fig. 3 is a perspective view of one of the gripping-dies. Fig. 4 is a perspective view of the two point-cutters and a portion of the wire-guide, showing the form of the cutters and their relative position with relation to the end of the wire-guide. Fig. 5 is a detail plan view of a portion of one gripping-die of the machine. Fig. 6 is a detail face view of a portion of the two gripping - dies of the machine, showing the manner in which they meet. Fig. 7 is a vertical longitudinal sectional elevation of the machine on line 1 of Fig. 1. Fig. 8 is a detail side view of the lower end of the header-arm. Fig. 9 is a cross-sectional view of the wire-feeding mechanism taken on line 2 of Fig. 1. Fig. 10 is a detail side view of the two point-cutters and a portion of the wire-guide, and also an end view of one of the gripping-dies, showing the manner in which the nails are lowered from the gripping-dies after they are headed and as their points are completed. Figs. 11, 12, and 13 are views of wire nails, being the product of the machine. Fig. 14 is a vertical cross-sectional elevation of the machine on line 3 of Fig. 1, looking in the direction of the arrow. Fig. 15 is a face plan view of the slotted disk for operating the wire-feeding mechanism of the machine, also show-

ing the adjustable crank-stud thereof and a portion of the pitman for connecting said disk with the reciprocating feeding grip-head. Fig. 16 is a horizontal cross-sectional view of a standard and cap-plate of the machine, taken on line 1 of Fig. 14, which parts are planed to form a perpendicular box in which is operated a chuck for holding the upper point-cutter, 55 the top plan of said chuck being shown in said view. Fig. 17 is a longitudinal sectional view of said chuck, also showing a shank and the upper point-cutter set therein. Fig. 18 is a perspective view of said chuck and its connected parts; and Fig. 19 is a side plan view of the heading-tool, showing the manner in which it is secured to the header.

Referring to the drawings, B represents the bed of the machine, which is rectangular in 70 form, and supported on the legs L and L'. L' represents a beam arranged between said legs below bed B, and is firmly secured to said legs by means of cap screws, as shown in Figs. 7 and 14.

B' is a bracket formed integral with bed B, and supports the reciprocating wire-feeding grip-head and guide, and also has secured to it a wire-straightener, T, for straightening the wire W as it is fed into the machine. (See 80 Fig. 1.)

B², B³, B⁴, B⁵, and B⁶ are boxes secured to bed B by means of cap-screws in the manner shown in Figs. 1 and 7, and are for the purpose of supporting the shafts S and S', as 85 shown in Fig. 1, the position of said shafts being also shown in Figs. 7 and 14 in cross-section. M represents a pair of miter-gears, which are keyed on said shafts in the manner shown in Fig. 1.

A is a belt-pulley secured on shaft S next to box B², (see Fig. 1,) and over which a belt may pass to operate the machine, and A' is a similar loose pulley arranged at the side of pulley A, and is for the purpose of holding 95 the driving-belt when it is desired to stop the movement of the machine, the driving - belt being shifted from the one to the other, to thus operate or stop the operation of the machine. A² represents a balance-wheel secured 100 to shaft S' next to box B⁶, as shown in Fig. 1, the momentum of which facilitates the successful operation of the machine.

H is a header-lever formed with an integral

downwardly-extending arm, H^2 , arranged to operate in an elongated opening through bed B and terminates in a fork forming a pair of ear-lugs, seated over a hub of beam L' and 5 pivotally secured to said beam by a pin, y , as shown in Fig. 7. (See also Fig. 14.)

E represents an eccentric secured on shaft S' between boxes B^4 B^5 , and is for the purpose of operating said header-lever through the 10 medium of the eccentric strap and arm E', connecting said eccentric with a pair of ear-lugs integral with the rear upper part of said header-lever by means of pin r , as shown in Figs. 1 and 7.

15 b and b' represent a pair of guide-plates secured to bed B by means of cap-screws, one at each side of said header-lever immediately below its enlarged upper part, (see Figs. 1 and 7,) and are for the purpose of properly 20 guiding said header-lever.

25 H' is a header screw-threaded about three-fourths its length, and is screwed into the header-lever in a corresponding screw-threaded hole bored in the face of said header-lever, and can be adjusted by either screwing it in or out of said hole, and can be held at any desired adjustment by a lock-nut, as shown in Figs. 1 to 7, and 19.

30 D represents a head secured to the upper surface of bed B, near one side, by means of cap-screws, and is for the purpose of holding the stationary gripping-die G, as shown in Figs. 1 and 7, and t, t', and t'' are set screws for adjusting and holding said die firmly in said head. D' is an extension or wing of said head arranged along the side of the wire-line, as shown in Figs. 1 to 7, and 14, and is for the purpose of supporting a guide for properly guiding the wire into the machine.

35 40 D' is a standard formed integral with head D, and is for the purpose of supporting the pivoted end of the upper lever, which operates the upper point-cutter. (See Figs. 1 and 14.)

45 K is a bracket secured to the under part of bed B, immediately below head D, by means of cap-screws. Said bracket has an integral depending ear-lug which supports the pivoted end of the lower lever, operating the lower 50 point-cutter. (See Fig. 14.) Said bracket also has a pair of integral depending ear-lugs, between which is pivoted the lower end of the arm of the oscillating grip-head of the machine. (See Fig. 7, and also dotted lines in Fig. 14.)

55 D' represents the oscillating grip-head arranged through an opening in bed B, and is formed with an integral downwardly-extending curved arm, which is pivoted between the 60 ear-lugs of bracket K, as described, by means of pin y' at a point directly under the wire-line. (See Fig. 7 and dotted lines in Fig. 14.)

I is an eccentric which is secured on shaft S between boxes B^2 and B^3 , and operates said 65 grip-head D' through the medium of the eccentric strap and arm I', connecting said eccentric with a pair of rear integral ear-lugs of

said grip-head by means of pin v^6 . (See Figs. 1 and 14). A cap-plate secured to the upper part of said head by means of cap-screws 70 and the set-screws v , v' , and v^2 serves to hold and adjust the gripping-die G', which is set in and operated by said head, as shown in Fig. 1 and by dotted lines in Fig. 14.

O represents a lever fulcrumed to the upper part of standard D' by means of pin m . Said lever has set therein the chuck g , into which is socketed the shank C^4 of the chuck, which holds the upper point-cutter. Said lever is operated through the medium of an eccentric strap and arm, J', by means of the eccentric J', keyed on shaft S, (see Figs. 1 and 14,) which eccentric is integral with and has an exact opposite throw from eccentric J. O' denotes a similar lever arranged below bed B, 80 fulcrumed to the depending lug of bracket K, as described, by means of pin m' , and has set therein the chuck g' , into which is socketed the shank C^5 of the chuck which holds the lower point-cutter. Said lever is operated by 85 means of the eccentric J through the medium of the eccentric strap and arm J'', which connects said eccentric with said lever, as shown in Fig. 14.

R is a cap-plate secured to the face of standard D' by means of cap-screws, as shown in Figs. 7 and 14. Said cap-plate has planed in its face next said standard a vertical angular recess, which is arranged opposite a corresponding angular recess planed in said standard, the two recesses thus forming a vertical box in which is arranged and operated the chuck for holding the upper point-cutter, as shown in Figs. 7 to 14, and 16, and R' denotes a similar plate having a similar recess. Said plate is secured at its lower end to the face of bracket K and extends up through an opening in bed B. Said plate is also secured to the base of head D in such manner as to support on its rear upper part the inner end of the wire-guide Z, (see Figs. 7 and 14,) and the said parts to which said plate is secured are similarly recessed to form a vertical box directly under the box of the chuck which holds the upper point-cutter, and on the opposite 115 side of the wire-line from said box, as shown in Figs. 7 and 14.

Z represents a wire-guide, which is arranged in a horizontal recess in the face of the extension or wing D' of head D in such manner that 120 its inner end will rest upon the rear part of plate R' and a short distance from the rear part of the gripping-dies G and G', as shown in Fig. 7, (see also Figs. 2 to 10, and 14,) and is held firmly in said recess by means of the clips 125 Z', held by cap-screws, as shown in Figs. 7 and 14. Said guide is constructed as shown in detail in Figs. 2 to 4, and 10, having the wire-channel Z' (see Fig. 4) planed in its body and rear part up to an offset near its inner end, 130 said inner end being bored to meet said channel, said bore being shown at Z' in Fig. 4. This hole is intended to be of a size corresponding with the gage of wire used. A cap-plate,

Z' , arranged over said channel Z^4 , serves to hold the wire W in said channel and complete the guide.

R^2 represents the chuck for holding the upper point-cutter, which is shown in Figs. 16, 17, and 18 and by dotted lines in Fig. 7. The shank C^4 is screwed into the upper part of said chuck, and is firmly secured by means of a lock-nut. Said shank connects said chuck with chuck g of lever O , as described, and is adjusted and held in said chuck g by means of set-screws f and f^2 , respectively, (see Figs. 7 and 14,) said screw f being secured by the lock-nut f' . Set in the lower part of said chuck R^2 is the upper point-cutter, C , arranged to operate between the rear part of the gripping-dies and the inner end of the wire-guide and to shear past the channel Z^3 of said guide. (See Figs. 4 to 7, and 10.) A corresponding chuck, R^8 , (see Fig. 7,) for holding the lower point-cutter, C' , is arranged in the lower vertical box, as described, and has a corresponding shank, C^6 , similarly secured in its lower end, and is socketed in chuck g of lever O' , as described, and is adjusted and held by means of set-screws X and X^2 , respectively, said screw X being secured by the lock-nut X' . (See Figs. 7 and 14.) Said point-cutter C' is arranged to operate exactly opposite cutter C , which is immediately below the wire, and in such manner that its cutting-edges will meet those of cutter C and cut the nail-points. The point-cutters C and C' are shown more particularly in Fig. 4. They are formed with oblique cutting-edges meeting at the side next the wire-guide Z , and with a cavity between the said oblique edges, having its inclined sides at right angles to one another, in such manner that when the two cutters meet the cavity between them will be pyramidal in form. The side portions of the operative ends of the said cutters, next the said wire-guide, are beveled to form said cutting-edges, while opposite said guide said portions are left intact, as shown in Fig. 4 at a and a' . When said cutters meet each other, said flat portions of cutter C register with those of cutter C' , and thus permit the said cutting-edges to meet close, but not engage each other sufficiently to result in injury, and by thus arranging said flattened portions at the outer side of and adjacent to the diverging part of said cutting-edges they are backed up and re-enforced to give them great strength, and, by arranging said flattened meeting surfaces at the opposite end from the angle of said cutting-edges permit the chip cut from the two sides of the nail-point to be readily discharged and render said cutting-edges more easily sharpened. The said cutters are so arranged and operated that they alternately recede from and advance toward each other, one either side of the wire-line.

When the machine is operating making nails, the upper cutter, C , will first engage the wire W , which has been fed forward far enough to form a nail and gripped between the gripping-dies. The upper cutter will meet the wire at

the place where it emerges from the guide Z , and as said cutter advances it will shear the blank square off from the main wire; but, however, before the wire is thus cut off, the lower cutter, C' , has advanced sufficiently to engage and hold the blank until the two cutters meet. As said cutters meet, they will cut a chip from either side of said blank and simultaneously compress the two opposite sides, and thus form a point on said blank pyramidal in form, corresponding with the form of the cavity of said cutters. At the time the cutter C engages the wire W , and before the blank is sheared loose from the main wire, the portion of wire which has been fed forward and projects from between the gripping dies, as shown by dotted lines in Fig. 2, is engaged by the heading-tool and formed into a nail-head, as shown in said figure, and thus while the said point-cutter C is in process of severing the blank loose from the main wire the nail-head is formed. The gripping-dies then release their grip on the partially-formed nail, and the two cutters in their joint operation of pointing the nail meet below the line of the main wire, and thus dislodge the nail from the gripping-dies and carry it below the line of the main wire and out of the way of the next succeeding nail, as shown in Fig. 10, and as said cutters recede from each other the completed nail is permitted to fall, and is caught and conducted from the machine by spout Q , (shown in Fig. 7,) which is secured to bracket K under the gripping dies.

F represents a reciprocating wire-feeding grip-head, (see Figs. 1 to 7, and 9,) and is arranged to reciprocate parallel with the wire-line upon guide e , which is secured on bracket B' by means of cap-screws.

d and d' are a pair of grip-dogs set in studs d' , which are pivotally secured in the upper part of head F , and said dogs are yieldingly held in contact with the wire W by means of coil-springs arranged on the extending shanks of said studs, as shown in Figs. 1 and 9. Said dogs are held in said studs by means of set-screws, and may be removed or adjusted when desired.

d^2 is a plate secured on a step of head F , under the dogs d , and is for the purpose of supporting the wire W in proper line, so the said dogs will properly engage it to feed it into the machine. Each end of said plate is turned up, and a hole is bored through said turned-up portions, which thus form guides to properly guide the wire across said plate.

P is a slotted disk secured on shaft S' at the outer side of box B^5 , as shown in Fig. 1. Said disk has secured in its face-slot a crank-stud, P^2 , in the ordinary manner, as shown in Figs. 1 and 15. Said disk is connected with and reciprocates head F through the medium of pitman P' , as shown in Fig. 1. Said crank-stud P^2 is adjustable in said slot, either to or from the center of said disk, so as to have the throw required to feed into the machine the proper length of wire at each movement. This ad-

justment is effected by means of screw P^t , which revolves in a plate secured to the periphery of said disk at one end of its face-slot. Said screw is secured into and through a tapped hole 5 in the head of stud P^2 , which slides in the said face slot. The face of said disk is provided with a scale, as shown in Fig. 15, and pitman P' has an indicating-point arranged to be moved along said scale, which is for the purpose of 10 facilitating in properly adjusting the feeding mechanism for different lengths of nails.

In Fig. 8 the forked ear-lugs of arm H^2 of header-lever H are represented as having a series of pin-holes for the reception of pin y , 15 and beam L has a corresponding series of holes which are for the purpose of changing the point of pivoting said arm, which becomes necessary when the machine is intended to make nails of different lengths in order that 20 the said point of pivoting can be directly under the point of heading. When long nails are being made, the gripping-dies are full width, and when shorter nails are being made the gripping-dies are cut away on their face 25 side, as shown in Fig. 5, and when full-width gripping-dies are used and long nails are being made the header-arm H^2 is pivoted at hole 1, (see Fig. 8), which is directly under the point of heading, and when medium-length 30 nails are being made said pivot would be at hole 2, and for short nails at hole 3. The construction of said header-arm with but one point of pivot, as shown in Fig. 7, is employed when 35 the machine is intended to make special-size nails.

n and h represent guides arranged at either side of the oscillating grip-head D' , as shown in Fig. 1, and are for the purpose of properly guiding said grip-head. A wedge-shaped 40 slide, n' , (shown by dotted lines in said figure) adjustably secured to the face of guide n , serves to take up the wear of said head and prevent lost motion, and also forms a solid backing for said grip-head to resist the blow of the header 45 against the gripping-dies.

The form of the operative portion of the gripping-dies G and G' is shown in Figs. 2 to 5, and 6, and especially in Fig. 3, and have a slight groove, a^4 , formed across the length of 50 their face on the wire-line, and are beveled each side from said groove, as shown at a^3 , Fig. 3, in such manner that should a nail get crosswise between them it will be cut in two and not strain or clog the machine, and the 55 parts where the heads of nails are formed are left intact a short distance back, as shown at a^2 in said figure, so as not to leave too great an opening between them when closed upon a nail (see Fig. 6) and to preserve the surface 60 against which the nail-heads are flattened. The said grooves a^4 of said dies are slightly countersunk where the nail-heads are formed of the style shown in Fig. 11, so as to form a slight fillet immediately beneath the heads of 65 said nails. Said dies are deeply countersunk where the nail-heads are formed of the style

shown in Fig. 13, in which case the heads are upset in said countersink; but when nail-heads are being formed of the style shown in Fig. 12 said grooves terminate at their face with 70 square shoulders and the heads are but slightly upset. The rear part of said grooves a^4 are enlarged and flared, as shown in Figs. 2 and 3, in order that the wire may more readily enter between them. 75

The gripping-dies G and G' and wire-guide Z may be removed and others substituted in their places, so as to accommodate wire of different caliber. The yielding qualities of the parts of the machine which are employed to 80 grip the nails assist eccentric I in holding the nails gripped a little longer than would be the case were said parts perfectly rigid, thus affording time for eccentric E to operate the heading mechanism to form the nail-heads; 85 and it would be quite difficult to so construct this machine that said parts would not be slightly yielding. The movements of the opposite parts of this machine, being produced by eccentrics in all important parts, enables it 90 to be run in either direction. A grip-dog may be secured to straightener T for preventing backward movement of the wire W ; but usually the frictional contact of said wire with the straightening-rolls is sufficient to hold it 95 from back movement. The wire W is threaded into the machine first between the rolls of straightener T , thence across the reciprocating head F , under the dogs d , and thence into guide Z , and when the machine is in operation the 100 wire is fed forward by the feeding mechanism far enough at each movement to emerge from guide Z and enter between and project a short distance beyond the gripping-dies, and during the process of feeding the said dies are being 105 closed, so as to form a guide for the end of the advancing wire and close upon it the instant it reaches its destination. The heading-tool and point-cutters advance toward the wire at the same time; but an instant later, while the grip 110 on the wire is greatest, the heading-tool meets the portion of wire projecting from the gripping-dies and upsets it to form a nail-head. During the process of heading the upper point-cutter is severing the partially-formed 115 nail loose from the main wire by shearing past the wire-guide. An instant later, as the oscillating gripping-die is receding, said upper point-cutter has dislodged the nail from the gripping-dies and carried it below the 120 wire-line to the point where said upper cutter meets the lower one, when the nail is formed complete and permitted to fall as the cutters separate. The nail is thus entirely out of the way for the next succeeding feed, as described. 125 During the process of forming a nail the feeding mechanism recedes, and when the nail-forming parts are open or apart from each other the next succeeding feed is made and another nail formed in like manner. Thus 130 each movement of parts which operate upon and form the nails is positively imparted by

an eccentric, and said parts work from pivot centers, which secure ease and speed in the movement of the machine.

Having thus described my invention, what 5 I claim as new, and desire to secure by Letters Patent, is as follows, to wit:

1. In the wire-nail machine shown and described, the gripping-head arranged through an opening in bed B and pivotally secured to bracket K below said bed, header-lever H H², similarly arranged at right angles with said gripping-head and pivotally secured to beam L' below said bed, and cutter-levers O and O', arranged, respectively, one above and one below said bed and pivotally secured to standard D² and bracket K, and each operating a nail-point cutter, in combination with stationary grip-head D, wire-guide Z Z', dies G G', header H', cutters C C', and eccentrics I, E, 20 J', and J and their respective straps and arms for respectively operating said parts, in the manner substantially as and for the purpose set forth.

2. In the wire-nail machine described, the 25 gripping-head D' and header-lever H H², respectively having the die G' and header H' above the machine-bed and pivoted to fixed bearings below said bed, in combination with stationary head D, bearing the grip-die G, and eccentrics I and E, arranged substantially as set forth, and co-operating to simultaneously grip and head a nail, in the manner substantially as specified.

3. In the wire-nail machine described, in 35 combination with the head D, having the grip-die G, the wire-gripping head D', having set therein a gripping-die and arranged to oscillate from a pivotal bearing below the machine-bed and at right angles with the wire-line by 40 means of eccentric I through the medium of a strap and arm, in the manner substantially as and for the purpose set forth.

4. In the wire-nail machine described, the 45 levers O and O', arranged, respectively, one above and one below the machine-bed and pivotally secured to standard D² and bracket K, respectively, in combination with the chucks R² and R⁸, nail-point cutters C and C', and eccentrics J' and J and their straps and 50 arms for respectively operating said parts, in the manner substantially as and for the purpose set forth.

5. In the wire-nail machine described, the header-lever H, having a pair of ear-lugs formed 55 on its rear upper part, and a downwardly-extending arm, H², terminating in a pair of ear-lugs forked over and pivoted to beam L', and having the adjustable nail-heading tool H' set therein, in combination with the eccentric E, 60 strap and arm E', and pin r, and the guide-plates b b, substantially as and for the purpose specified.

6. In the wire-nail machine described, the 65 gripping-head D', having a pair of ear-lugs formed on its rear upper part and a downwardly-extending curved arm pivotally secured between a pair of stationary ear-lugs,

and having the adjustable gripping-die G' set therein, in combination with eccentric-strap I and arm I', guides n and h, and the head D, 70 having the stationary gripping-die G set therein, substantially as and for the purpose set forth.

7. In the wire-nail machine described, the combination of the levers O and O', respectively fulcrumed to stationary bearings of the machine, one above and one below bed B, and respectively provided with the chucks g and g', with the eccentrics J J' and straps and arms J' J², shanks C⁴ C⁵, chucks R² R⁸, and 80 point-cutters C and C', substantially as and for the purpose set forth.

8. In the wire-nail machine described, the gripping-dies G and G', grooved as set forth and beveled on each side, forming a cutting-edge at each side of said groove and having square portions at the place where the nail-heads are formed, substantially as and for the purpose specified.

9. In the wire-nail machine described, the 90 combination of the stationary gripping-die G and horizontally-operating gripping-die G', arranged facing each other, header H', arranged facing said gripping-dies, wire-guide Z, arranged to conduct the wire between said dies, and the reciprocating nail-point cutters C and C', arranged to operate between said gripping-dies and wire-guide, in the manner substantially as and for the purpose set forth.

10. In the wire-nail machine described, the 95 chucks g and g', respectively seated and arranged to oscillate in levers O and O', in combination with said levers and the point-cutter chucks and point-cutters C and C', substantially as and for the purpose set forth.

11. In the wire-nail machine described, the 100 chucks R² and R⁸, respectively having the shanks C⁴ and C⁵, and arranged to operate in vertical boxes and hold the point-cutters in such manner that they face each other, in combination with the chucks g and g' and levers O and O', substantially as and for the purpose set forth.

12. In the wire-nail machine described, the 105 disk P of the feeding mechanism, having a scale and an adjusting-screw, as specified, in combination with pitman P and the reciprocating feeding grip-head F, substantially as and for the purpose set forth.

13. In the wire-nail machine described, the 110 chucks R² and R⁸, arranged in vertical boxes facing each other and respectively having the nail-point cutters C C' and the wire-guide Z, fixed in a position at right angles with said cutters and arranged to conduct wire between 115 said cutters, all combined and operating in the manner substantially as and for the purpose set forth.

14. In the wire-nail machine described, in 120 combination with the gripping, heading, and point-cutting mechanisms, constructed substantially as described, the reciprocating feeding grip-head F, having the spring-grip dogs d d and plate d², and arranged on guide e, and

operated in the manner substantially as set forth.

15. In the wire-nail machine shown and described, the combination, with bed B and boxes 5 B², B³, B⁴, B⁵, and B⁶, of the shaft S, having the pulleys A and A', eccentrics I, J, and J'', and a miter-gear, M, and shaft S', having the balance-wheel A², eccentric E, feed-disk P, and a miter-gear, M, and united by said gears and 10 arranged to operate the feeding, gripping, heading, and pointing mechanism of the machine, in the manner and for the purpose set forth.

16. In the wire nail machine described, in 15 combination with wing D⁴, the wire-feeding mechanism and point-cutters C C' and the guide Z, constructed and arranged in the manner substantially as set forth.

17. In the wire-nail machine described, the 20 combination of the header-lever H H' and beam L', each having a series of pivot-holes, 1 2 3, pin y, and adjustable header H', substantially as and for the purpose set forth.

18. In the wire-nail machine described, in 25 combination with levers O and O' and chucks g and g', the chucks R² and R³, respectively having the shanks C⁴ and C⁵ and the set-screws f² and X X², substantially as and for the purpose set forth.

30 19. In the wire-nail machine described, in combination with the bed B, the head D, having standard D², bracket K, and cap-plates R R', arranged to form vertical boxes, substantially as specified, and the chucks R² and R³, 35 operating in said boxes in the manuer and for the purpose set forth.

20. In the wire-nail machine described, in

combination with the nail-point cutters C and C', the chucks R² and R³, having chambers, as 40 shown, for the reception of said cutters, and respectively provided with the adjustable shanks C⁴ and C⁵, screwed therein, as set forth, and arranged to operate in the manner substantially as specified.

21. In the wire-nail machine described, in 45 combination with their respective chucks, the nail-point cutters C and C', having oblique cutting-edges arranged to register with each other, and respectively having the flattened portions or meeting surfaces a a and a' a' arranged at 50 the outer sides of and adjacent to the diverging ends of said cutting-edges, and leave the said cutting-edges unobstructed at their outer sides at their respective angles, substantially as and for the purpose set forth.

22. In the wire-nail machine described, the combination of the gripping-dies G and G', having cavities in their engaging-faces fitting the nail-wire, header H', arranged in line with said cavities and adapted to move toward and 60 from said dies to engage and form a nail-head on the wire projecting from said dies, wire-guide Z, arranged in line with said die-cavities on the opposite side of said dies from said header, and the nail-point cutters C and C', arranged to operate transversely from said die-cavities between said dies and guide to sever a nail loose from the nail-wire and cut and 65 form the nail-points and dislodge the nail from the gripping-dies, substantially as set forth.
